UNITED STATES PATENT OFFICE

157,325

WALL COVERING OR THE LIKE

A. Baker Barnhart, New York, N. Y.

Application July 6, 1949, Serial No. 3,721

Term of patent 14 years

(Cl. D59—10)

To all whom it may concern:

Be it known that I, A. Baker Barnhart, a citizen of the United States, residing in New York city, in the county of New York and State of New York, have invented a new, original, and ornamental Design for a Wall Covering or the like, of which the following is a specification, reference being had to the accompanying drawing, forming part thereof.

The figure is a plan view of a wall covering or the like, showing my design.

I claim:

The ornamental design for a wall covering or the like, substantially as shown.

A. BAKER BARNHART.
